Charles Gibbons ^{Inventor}
By Louis B. Geer ^{Attorneys}

UNITED STATES PATENT OFFICE.

CHARLES GIBBONS, OF BAKER, OREGON.

AUTOMOBILE TOOL BOX.

Application filed January 27, 1921. Serial No. 440,348.

To all whom it may concern:

Be it known that I, CHARLES GIBBONS, a citizen of the United States, residing at Baker, in the county of Baker and State 5 of Oregon, have invented certain new and useful Improvements in Automobile Tool Boxes, of which the following is a specification.

My invention relates to an improvement 10 in automobile tool boxes.

The purpose of the invention is to provide a compact and convenient arrangement for carrying tools and protecting them while being carried, both from the elements and 15 from being removed by an unauthorized person.

This invention includes a box having an arrangement for one or more drawers therein, with a shallow recess or compartment 20 formed in the bottom in connection with the lower drawer, which latter has parallel transverse runners on the bottom, which have sliding connection with the ends of the shallow compartment, thereby helping to close 25 the latter tight, and also forming guides for the travel of the drawer in and out of the box.

This invention further consists in a drop door arranged to form a shelf substantially 30 flush with the bottom when open, to make it convenient for the operator to handle his tools.

In the accompanying drawings:

Fig. 1 is a view in perspective of the box 35 when open;

Fig. 2 is a longitudinal section;

Fig. 3 is a transverse section taken through the shallow receptacle at the bottom, and through one of the hinges.

40 Figure 4 is a sectional view on the line 4—4 of Figure 3.

Figure 5 is a perspective view of the lower drawer.

A, represents the box, and 1 is the cover 45 or lid connected thereto by the hinges 2 at the bottom, and the hinges are so arranged that the door or lid is substantially flush with the bottom when open, and closes tight against the open side of the box when shut.

50 A support in the form of two links 4 and 5 pivoted together is pivotally connected to the box and cover to limit the downward movement of the latter to a horizontal position.

55 The box is preferably divided into two

compartments by a horizontally disposed shelf 6, although obviously there might be more or even less compartments. A drawer H slides over the upper compartment. This may be in any approved form with partitions or not, with a drop handle 8 hinged at the front adapted to drop out of the way of the cover, when the box is closed. A shallow compartment 9 is formed on the bottom of the box by means of the end and 60 front cleats 10, the same being adapted to receive papers or cards or thin articles which need to be carefully protected and preserved.

The lower drawer 11 slides over these cleats and is provided with the transversely 65 extending parallel runners 13, which span the end cleats and form guides as well as means for assisting in tightly closing the ends of the shallow compartment.

In this way, the drawer is guided evenly, 70 and the contents of the shallow compartment is well protected.

Ledges 14 are formed around the top and end edges of the door to protect the contents from rain and the like. The door is 75 provided with a lock 15 for fastening the same.

The box might be fastened in place or 80 not, as desired, and might be provided with a handle or handles.

The drawers may be partly withdrawn 85 or removed and supported on the door as a shelf, if desired, or one could be placed there, and the other drawer partly withdrawn, thus 90 making it convenient to get out all the tools at any time without the bother of repeatedly sliding the drawers in and out.

I claim:

1. A tool-box including a door hinged at the bottom and adapted to serve as a shelf 95 when open, a shallow recess or compartment formed on the bottom of the box, and a drawer having runners which span the ends of the raised shallow recess or compartment to facilitate sliding the latter in and out. 100

2. The combination with a box, a door hinged at the bottom, and having a folding support, whereby the downward movement of the door is limited to horizontal, so that it may serve as a shelf, of one or more 105 drawers slidable within the box, one having transversely disposed tracks on the bottom, and the bottom of the box provided with a shallow recessed compartment or recess which the runners of the lower drawer span, 110

whereby the contents is better protected, and the sliding of the drawer in and out is facilitated.

3. The combination with a box and a cover or lid hinged at its lower edge to the outer edge of the bottom of the box, of a support in the form of links connected with the cover or lid, and with the box, and of

a length to limit the downward movement of the lid or cover to a position in alignment with the bottom of the box, and a drawer slideable in the bottom of the box in position to be pulled out upon the cover or lid as a shelf when the latter is open.

In testimony whereof I affix my signature.

CHARLES GIBBONS.
